(57) **CLAIM**

The ornamental design for a “camera support,” as shown and described.

DESCRIPTION

FIG. 1 is a top, front, and right side perspective view of a camera support, showing our new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a top, front, and right side perspective view thereof attached to a camera showing a state of use; and,

FIG. 10 is a top and front side perspective view of the camera support, along the viewing direction of line 10-10 from FIG. 5 perpendicular to a top flange structure of the camera support.

The broken lines in the figures illustrate portions of the camera support that form no part of the claimed design. The additional broken lines in FIG. 9 represents environmental subject matter and form not part of the claimed design.
